(57) **CLAIM**

The ornamental design for a washcloth, as shown and described.

DESCRIPTION

FIG. 1 is a top right perspective view of a washcloth of our new design;

FIG. 2 is a front view thereof;

FIG. 3 is a rear view thereof;

FIG. 4 is a right side view thereof, the left side view being a mirror image thereof; and,

FIG. 5 is a top view thereof, the bottom view being a mirror image thereof.

The broken lines shown in the drawings represent features of the washcloth in FIGS. 1-3 that form no part of the claimed design.

1 Claim, 5 Drawing Sheets

Related U.S. Application Data

a continuation-in-part of application No. 17/177,139,
filed on Feb. 16, 2021, now Pat. No. 11,185,208.
